Primary Examiner — Cynthia Ramirez

(57) **CLAIM**

The ornamental design for a forklift attachable pusher, as shown and described.

DESCRIPTION

FIG. 1 is a front-top-right perspective view of a forklift attachable pusher showing my new design;
 FIG. 2 is a rear-top-right perspective view thereof;
 FIG. 3 is a rear-bottom-left perspective view thereof;
 FIG. 4 is a front elevational view thereof;
 FIG. 5 is a rear elevational view thereof;
 FIG. 6 is a left elevational view thereof;
 FIG. 7 is a right elevational view thereof;
 FIG. 8 is a top plan view thereof;
 FIG. 9 is a bottom plan view thereof; and,
 FIG. 10 is a reduced front-top-right perspective view of the forklift attachable pusher in condition of use.
 The broken lines showing fasteners in FIGS. 1 through 10 and the broken lines showing a forklift in FIG. 10 are included for the purpose of showing environmental structure and form no part of the claimed design.

1 Claim, 10 Drawing Sheets(56)
